UNITED STATES PATENT OFFICE.

HARRY WIARD, OF SYRACUSE, NEW YORK.

DESIGN FOR A SHIN-PIECE FOR MOLDBOARDS FOR PLOWS.

SPECIFICATION forming part of Design No. 27,349, dated July 13, 1897.

Application filed May 28, 1897. Serial No. 638,637. Term of patent 14 years.

To all whom it may concern:

Be it known that I, HARRY WIARD, of Syracuse, in the county of Onondaga, in the State of New York, have invented and produced a new and original Design for a Steel Shin-Piece for the Moldboard of a Plow, of which the following is a specification, reference being had to the accompanying drawings, showing a part thereof.

10 Figures 1 and 2 are respectively face and side elevations of a shin-piece embodying my design, and Fig. 3 is an enlarged inverted plan view of said shin-piece.

15 The leading feature of my design consists in a steel shin-piece for the moldboard of a plow, which shin-piece when viewed in face and side elevations presents a concavo-convex appearance and when viewed in plan presents the appearance of an L.

20 A is a steel shin-piece embodying my design. The front and rear faces a a' of the shin-piece A are respectively substantially

concave and convex. The front face a is formed at one side with a lengthwise angular groove a^2 , which causes the shin-piece A to 25 present the appearance of an L when viewed in plan.

A shin-piece for the moldboard of a plow embodying my design presents a graceful, pleasing, and characteristic appearance. 30

What I claim is—

The design for a shin-piece for the moldboard of a plow, substantially as herein shown and described.

In testimony whereof I have hereunto signed my name, in the presence of two attesting witnesses, at Syracuse, in the county of Onondaga, in the State of New York, this 1st day of May, 1897.

HARRY WIARD.
